Primary Examiner — Mitchell I. Siegel

(74) Attorney, Agent, or Firm — Casey H. Kempner;
Siamak S. Hefazi(57) **CLAIM**

The ornamental design for a hockey stick, as shown and described.

DESCRIPTION

FIG. 1 is a perspective view of a hockey stick showing the claimed design;

FIG. 2 is a left-side view thereof;

FIG. 3 is a right-side view thereof;

FIG. 4 is a bottom view thereof;

FIG. 5 is a top view thereof;

FIG. 6 is a front view thereof; and,

FIG. 7 is a back view thereof.

Broken lines in the figures show portions of the hockey stick that form no part of the claimed design.
